(57) **CLAIM**

The ornamental design for a fluid container holder, as shown and described.

DESCRIPTION

FIG. 1 is a top perspective view of a fluid container holder showing my new design;

FIG. 2 is another top perspective view thereof;

FIG. 3 is a front elevational view thereof;

FIG. 4 is a rear elevational view thereof;

FIG. 5 is a top plan view thereof;

FIG. 6 is a bottom view thereof;

FIG. 7 is a right-side elevational view thereof; and,

FIG. 8 is a left-side elevational view thereof.

The broken lines shown in the drawings are for the purpose of illustrating portions of the fluid container holder, which form no part of the claimed design.

1 Claim, 8 Drawing Sheets
